LIFTING JACK

Gustave E. Le Veque, Detroit, Mich.

Substituted for abandoned application Serial No. 364,801, November 8, 1940. This application January 31, 1945, Serial No. 575,405

3 Claims. (Cl. 254—97)

This application is a substitute for my abandoned application Serial No. 364,801 filed on November 8, 1940.

My invention relates to an improvement in lifting jacks.

The object of the present invention is to provide a light, simple form of lifting jack, consisting of a minimum number of parts and one which can be manufactured at a minimum expense and marketed at an attractive price.

A further object is to provide a structure in which the component parts, when once assembled thereafter become a single unit, that is to say, all parts in one mechanism.

Another object is to provide a jack which will occupy relatively small space when carried in a car, light in weight so that it may be easily lifted and placed in position and, above all, which is capable of being operated easily and with very slight exertion of effort on the part of the operator whether man, woman or child.

With these and other objects in view, the present invention consists of a rack bar extending upwardly from a suitable base, and a housing through which the rack bar extends and within which housing there are rotatably mounted suitable shafts and gears which, when turned, raise or lower the housing along with the mechanism carried therein, upon the rack bar, locking the housing at each point to which it may be raised or lowered.

The invention also consists in more detailed mechanism which will be hereinafter fully described and pointed out in the claims.

In the accompanying drawing:

Figure 1 is a view in perspective of my improved jack.

Figure 2 is an enlarged vertical sectional view, on the line 2—2 of Figure 3, looking toward the right.

Figure 3 is a vertical sectional view, on the line 3—3 of Figure 2.

Figure 4 is a horizontal sectional view on the line 4—4 of Figure 3.

Figure 5 is a vertical sectional view on the line 5—5 of Figure 3 looking toward the right.

The numeral 1 represents a rack or rack tooth bar supported pivotally or otherwise by means of the pin 2 in the base 3 at the bottom, so that it is given limited play back and forth. If extreme economy and lightness is desired, the base 3 may be omitted and the rack 1 permitted to bear directly on the pavement or road surface when the jack is in use.

In the present form of my invention, a housing

4 is provided which contains the operating mechanisms. The housing 4 is more or less cubical in shape, open at the top and bottom as indicated by numerals 5 and 6 and provided on two opposite sides with the gores 7 and 8 which are employed as a lifting head and which are designed to engage the bumper of the vehicle which is to be raised. One of the internal corners of the housing, which may be formed by casting, is shaped as at 9 to embrace a portion of the periphery of the rack 1. This insures bearing contact of sufficient area between the housing 4 and the rack 1 to provide the necessary strength and to take care of any lateral thrust due to the weight of the object resting upon the jack when in use.

The mechanism for operating the jack which really constitutes the spirit of my present invention will now be described.

A worm 10 is mounted to turn within the housing, as shown in Figure 2. The ends of the worm 10 are bearings 11 and 12 which bearings are rotatably supported in openings 13 and 14 in opposite walls of the housing 4. At one extremity of the worm 10 is a pin 15 which maintains 15 the worm in assembled position. At the other end of the worm 10, a ball bearing indicated as 16 is provided. This is rotatably mounted on the bearing portion 12 of the worm 10 which, it will be noted is of lesser diameter than the remainder 20 of the worm and consists of an inner race 17 whose plane face bears against the housing 4 and a complementary outer race also rotatably mounted, each race having a grooved raceway as at 19 and 21 respectively. A number of ball 25 bearings are disposed in the raceways to take the thrust which is in the direction of the arrow 23 in Figures 2 and 5 when worm 10 is rotated for lifting housing 4. The end of the worm 10 is provided with a right-hand thread 24 and engaging 30 this is the handle 25 and hold-on nut 26, both of which may be tapped to engage this thread.

A shaft 27 extends through openings 28 and 29 in opposite walls of the housing 4. Rotatably mounted on shaft 27 are a worm gear 30 and a pinion 31. The worm gear and pinion are secured to each other and turn together on shaft 27. The worm gear 30 meshes with worm 10. The pinion 31 has relatively few teeth but is designed to have great strength and meshes with rack 1, this combination being clearly shown in Figure 2. Inspection of Figure 3 will show that worm gear 30 has a collar 32, the face of which bears against the inner face of housing 4. Similarly, pinion 31 has a bearing surface 33 which bears against the opposite internal face of hous-

ing 4. The combined length of worm gear 30 and pinion 31 is such that they fit within the opposite walls of the housing freely but without undue play. The result is that the housing confines these operating parts and counters the thrust developed when the jack is in use.

In assembling the parts composing this invention, the worm is inserted in the housing from right to left in Figure 2 through holes 13 and 14 until the collar thereon formed by the reduced diameter bearing section 12 seats against the interior of the left wall of the housing. The bearing and handle assemblies are then mounted on the worm. The combined worm gear and pinion is then taken and the teeth of the pinion meshed with the teeth of the rack 1. This sub-assembly is then inserted in the housing 4 from the bottom upwards in Figure 2 until the teeth of worm gear 30 mesh properly with the teeth of worm 10. The rack 1 is then supported by the groove 9 in housing 4 previously described and shown in Figure 4. The shaft 27 which has a formed head 34 at its right end is then inserted through opening 29 in the right wall of housing 4, through the central apertures of pinion 31 and worm gear 30, and finally through opening 28 in the left wall of housing 4. The left end of shaft 27 may then be upset as at 35 to maintain the assembly in place.

This assembly is easy and practical and it should be noted that the housing is so designed that it counters the thrust developed in the jack's operation and holds all the components in an integrated whole. It is further apparent that the mechanical advantage traced through the lever action of the handle 25 and the ratios of the gears constituting the train is very great so that the jack may be operated with a minimum of impressed force. Friction, insofar as possible, is minimized with a consequent increase in efficiency. The structure of the gear train is such that the jack is self-locking under load and is smooth and continuous in operation.

What I claim is:

1. In a lifting jack, the combination of a lifting bar substantially cylindrical in cross-section having rack teeth formed on a part of its surface, a unitary housing having a substantially rectangular hollow cross-section, notches formed in two opposite walls of said housing forming a lifting head, one interior corner of said housing being formed to conform to and provide a bearing for a portion of the circumference of said

bar, a worm gear, a pinion secured thereto, said worm gear and pinion being mounted on a shaft journalled in two opposite walls of said housing, a worm journalled in the other two opposite sides of said housing and meshing with said worm gear, the teeth of said pinion meshing with said rack teeth, means for turning the worm, endwise movement of the worm gear and pinion in each direction being opposed by opposite inner walls of the housing, and endwise movement of the worm gear in response to the lowering action being directly resisted by an inner wall of said housing.

2. In a lifting jack, the combination of a lifting bar substantially cylindrical in cross-section having rack teeth formed on a part of its surface, a one-piece hollow housing substantially rectangular in cross-section, a lifting head formed in the walls of said housing, one interior corner of said housing being shaped to conform to and provide bearing for a portion of the circumference of said bar, a worm gear and a pinion adapted to rotate together and to be inserted in said housing, said worm gear and pinion being secured therein by a pin transversing opposite walls of said housing, a worm, a shoulder and bearing formed at one end of said worm, said worm adapted to be inserted through journals of the other opposite walls of said housing and said shoulder bearing against the inner surface of one of said walls, and securing means beyond said shoulder on said worm whereby said worm is secured in said housing.

3. In a lifting jack, the combination of a rack, a unitary housing having a substantially rectangular hollow cross-section having notches in the walls thereof defining a lifting head thereon, and open at at least one end, said rack extending through said housing, a worm and shaft rotatably supported in opposite walls of said housing, a collar formed adjacent one end of said shaft and engaging the inner surface of one of said opposite walls of said housing, retaining means secured to said shaft adjacent said end and engaging the outer surface of the said wall of said housing, the other end of said shaft being slidably received in the other of said opposite walls, a second shaft journalled in a second pair of opposite walls of said housing, said second shaft having rotatably mounted thereon a worm gear and a pinion, said worm engaging said worm gear and said pinion engaging said rack.
